(57) **CLAIM**

The ornamental design for a telephone handset, as shown and described.

DESCRIPTION

FIG. 1 is a top-front-left perspective view of a telephone handset showing my new design;

FIG. 2 is a bottom-back-right perspective view thereof;

FIG. 3 is a front view thereof;

FIG. 4 is a back view thereof;

FIG. 5 is a left-side view thereof;

FIG. 6 is a right-side view thereof;

FIG. 7 is a top view thereof; and,

FIG. 8 is a bottom view thereof.

The dot-dot broken lines are for illustrative purposes only and form no part of the claimed design.

The thin, black lines shown in long dashes with intermittent breaks are shading and/or tangent lines to show contour of the surfaces or curved edges of a telephone handset, and do not actually appear on the surface of the device.
